UNITED STATES PATENT OFFICE.

EDWARD J. KING AND THOMAS R. KENNEDY, OF ROCHESTER, NEW YORK,
ASSIGNORS TO THE COOPERATIVE FOUNDRY COMPANY, OF SAME
PLACE.

DESIGN FOR A COOKING-STOVE.

SPECIFICATION forming part of Design No. 24,477, dated July 16, 1895.

Application filed May 23, 1895. Serial No. 550,457. Term of patent 7 years.

To all whom it may concern:

Be it known that we, EDWARD J. KING and THOMAS R. KENNEDY, of Rochester, in the county of Monroe and State of New York, have invented and produced a new Design for Cooking-Stoves; and we do hereby declare the following to be a description of the same, taken in connection with the accompanying drawings, in which—

10 Figure 1 is a perspective view of a stove embodying our design, and Fig. 2 a similar view showing the front end of the stove on a larger scale than in Fig. 1.

The leading and characteristic features of 15 our design are the configuration and surface ornamentations of the stove as a whole and of the several segregable features thereof, to be hereinafter pointed out, and which are illustrated in the drawings.

20 The base of the stove-body, indicated by A, has its upper portion rounded and provided with the surface ornamentation B, composed of scrolls and conventionalized leaves, and the legs C at the corners of said base are provided 25 with the scroll and conventionalized leaf ornamentation D.

E indicates the hearth, having the depending smooth rim E' and beneath it the ash-pit section F, inclined at the front and ornamented at the sides by the ribs f and at the lower corners and front by the scroll ornamentation f', as shown more particularly in Fig. 2. At the rear corner of the hearth E is the bracket G, ornamented in relief, as shown.

30 H indicates the oven-door, having the rounded edges h and the ornamental scroll-work in the nature of a border, embodying a series of rounded ornaments H' in high relief, resembling conventionalized fruit, from which 35 extend scrolls and conventionalized leaf ornamentation H².

J indicates the central panel of the oven-door ornamented, as shown, with the scroll-work j in relief.

40 K indicates the fire-pot door, having near the front of the stove the rounded ornaments

k in relief, from which extends the scroll work k', also in relief.

L indicates the front ash-pit door, having the rounded edges at the top and sides and 50 provided with the central ornament L' and the scroll and leaf ornamentation L² around it and extending down the sides.

Above the front ash-pit door is the front panel M, rounded forwardly and upwardly 55 from above the front ash-pit door L toward the top of the stove and covered with the surface ornamentation M' in relief, consisting of scrollwork, while the vertical panels N at the sides of the door L are provided with the 60 ornamental scrollwork in relief, as shown.

O indicates the reservoir-panel, having the general smooth surface rounded, as shown, and provided with the surface ornamentation O' in relief, a portion extending down around 65 the lower edge of said panel, which is of irregular outline and rises in a series of curves toward the rear.

P indicates the smooth depending border or flange at the top of the stove. 70

Q indicates the oven-shelf beneath the oven-door, having the rounded front edge and the surface ornamentation in low relief, as shown.

R indicates the small shelf arranged beneath the fire-pot door K and having a 75 smooth edge.

We claim—

1. The design for stoves substantially as herein shown and described.

2. In the design for stoves, the design for 80 the base and legs, substantially as shown and described.

3. In the design for stoves, the design for the oven-door, substantially as shown and described.

4. In the design for stoves, the design for the ash-pit section F, substantially as shown and described. 85

5. In the design for stoves, the design for the front, comprising panel M, and the vertical panels N, substantially as shown and described. 90

6. In the design for stoves, the design for the front ash-pit door L, substantially as shown and described.

7. In the design for stoves, the design for 5 the reservoir panel O, substantially as shown and described.

8. In the design for stoves, the design for the oven-shelf Q, substantially as shown and described.

9. In the design for stoves, the design for 10 the fire-pot door K, substantially as shown and described.

EDWARD J. KING,
THOMAS R. KENNEDY.
